UNITED STATES PATENT OFFICE.

WILLIAM McCABE, OF ST. LOUIS, MISSOURI, ASSIGNOR TO THE ST. LOUIS CORSET COMPANY, OF SAME PLACE.

DESIGN FOR A CORSET.

SPECIFICATION forming part of Design No. 18,825, dated December 25, 1888.

Application filed May 14, 1888. Serial No. 273,875. Term of patent 3½ years.

To all whom it may concern:

Be it known that I, WILLIAM McCABE, a citizen of the United States, residing at St. Louis, in the State of Missouri, have invented 5 and produced a new and useful Design for a Corset, of which the following is a specification, reference being had to the accompanying drawings, forming part thereof.

Figure I is a perspective view of my newly-10 designed corset. Fig. II is a side view showing one-half of the corset. Fig. III is a perspective view of a modified form.

The essential features of my design consist in the gore-shaped pieces at the sides of 15 the waist portion, the upright strips at the outer edges of the gore-shaped pieces, the upright webs pointed at their tops, the upright strip separating the upright pointed webs, and the semi-oval pieces above and beneath 20 the gore-shaped pieces and between the pointed webs.

1 represents paired webs pointed at their

upper ends and apparently separated by upright strips 8, and having semi-oval pieces 9 between their points. 25

2 represents rear upright strips. On the inner sides of the paired webs I represent upright strips 7, and on the inner sides of the rear strips I show similar strips, 7^a. At the waist portion of the sides I represent gore-shaped pieces 4 between the upright strips 7 and 7^a. These gore-shaped pieces are represented as separated by upright pieces 3 or (as shown in the modification) by lacing 6. Above and beneath the gore-shaped pieces 30 appear semi-oval pieces 5.

I claim as my invention—

The design for a corset, substantially as herein described and shown.

WM. McCABE.

In presence of—

JOS. WAHLE,
GEO. H. KNIGHT.
